(57) **CLAIM**

The ornamental design for an teeth for a ripper (part of excavator), as shown and described.

DESCRIPTION

FIG. 1 is a perspective view of an excavator showing my new design, according to a first embodiment;

FIG. 2 is a front/back view of the design shown in FIG. 1; FIG. 3 is a left side/right side view of the design shown in FIG. 1;

FIG. 4 is a top view of the design shown in FIG. 1; FIG. 5 is a cross section 5-5 view of the design shown in FIG. 3;

FIG. 6 is a cross section 6-6 view of the design shown in FIG. 4;

FIG. 7 is a perspective view of a second embodiment thereof; FIG. 8 is a front/back view thereof;

FIG. 9 is a left side/right side view of the design shown in FIG. 7;

FIG. 10 is a top view of the design shown in FIG. 7;

FIG. 11 is a cross section taken along line 11-11 in FIG. 9; FIG. 12 is a cross section taken along line 12-12 in FIG. 10;

FIG. 13 is a perspective view of a third embodiment thereof; FIG. 14 is a front/back view thereof;

FIG. 15 is a left side/right side view of the design shown in FIG. 13;

FIG. 16 is a top view of the design shown in FIG. 13;

FIG. 17 is a cross section taken along line 17-17 in FIG. 15; FIG. 18 is a cross section taken along line 18-18 in FIG. 16;

FIG. 19 is a perspective view of a fourth embodiment thereof; FIG. 20 is a front/back view thereof;

FIG. 21 is a left side/right side view of the design shown in FIG. 19;

FIG. 22 is a top view of the design shown in FIG. 19;

FIG. 23 is a cross section taken along line 23-23 in FIG. 21; and,

FIG. 24 is a cross section taken along line 24-24 in FIG. 22.
